United States Patent Office

Des. 203,048
Patented Nov. 30, 1965

203,048

CONTROL CONSOLE

Marion Pastoric, Chesterland, Robert J. Perry, Willowick,
and Kenneth A. Wood, Chesterland, Ohio, assignors to
Bailey Meter Company, a corporation of Delaware

Filed Apr. 12, 1965, Ser. No. 84,737

Term of patent 14 years

(Cl. D26—5)

FIG. 1

FIG. 3

FIG. 2

FIG. 1 is a front perspective view of a control console showing our new design.

FIG. 2 is a side elevational profile view of the console shown in FIG. 3.

FIG. 3 is a front elevational view of the console.

The side not shown is substantially a mirror image of the side shown, while the back of the console is plain and unornamented.

The essential features of the design are shown in full lines.

We claim:

The ornamental design for a control console, substantially as shown and described.
